UNITED STATES PATENT OFFICE.

NORMAN E. BROWN, OF ST. JOSEPH, MICHIGAN, ASSIGNOR, BY MESNE ASSIGNMENTS,
TO WIREBOUNDS PATENTS COMPANY, OF KITTERY, MAINE, A CORPORATION OF
MAINE.

MACHINE FOR USE IN MAKING METAL-BOUND PACKAGES.

1,276,484.

Specification of Letters Patent. Patented Aug. 20, 1918.

Application filed October 29, 1904, Serial No. 230,478. Renewed December 29, 1916. Serial No. 139,649.

To all whom it may concern:

Be it known that I, NORMAN E. BROWN, a citizen of the United States of America, and resident of St. Joseph, Berrien county, Michigan, have invented a certain new and useful Improvement in Machines for Use in Making Metal-Bound Packages, of which the following is a specification.

This invention relates to the manufacture of wire-bound boxes and pertains more particularly to combined fastener-applying and work-controlling mechanisms for use in manufacturing box blanks, or sections of blanks, formed of side sheet material, separate or individual cleats, and reinforcing wires arranged to be secured to the side sheet material and individual cleats.

In a machine embodying this invention the fastener-applying mechanism and the work-controlling means coöperate to produce box-blanks or blank-sections of the character suggested with rapidity and accuracy of relative adjustment of the side sheet material, individual cleats and wires, which is extremely desirable. One of the principal objects of the invention is to provide guiding means for effectually insuring the proper relationship between the box parts and the fastener-applying means during the application of fasteners.

The invention is hereinafter described for illustration, as embodied in an organized machine comprising fastener-applying means, work-controlling means arranged to present to said fastener-applying means the parts of a blank for a sectional box, and guiding means operatively associated with the work-controlling and fastener-applying mechanisms for insuring that the work shall be presented in desired position relative to the fastener-applying means. In the specific illustrative machine, the said elements coöperate to drive staples, in desired positions, astride of binding wires, through side sheet material and into the individual cleats.

In the accompanying drawings,—

Figure 1 is a side elevation of a machine embodying the principles of my invention.

Fig. 2 is an enlarged longitudinal section through the central portion of the same.

Fig. 3 is a rear elevation of the machine shown in Fig. 1.

Fig. 4 is an enlarged detail longitudinal

section of the central portion of the machine.

Fig. 5 is a plan on a similar scale of the machine shown in Fig. 1.

Fig. 6 is a perspective of the removable or portable work-holder which carries the work through the machine.

Fig. 7 is a perspective of one of the finished box blanks made by a machine constructed in accordance with my invention.

Fig. 8 is an enlarged plan of one side and corner portion of the said work-holder.

Fig. 9 is an enlarged longitudinal section through a portion of the box blank resting upon one side of the said work-holder.

Fig. 10 is a cross section on line 10—10 in Fig. 8.

As thus illustrated, my improved box-blank making machine comprises a suitable frame or body A adapted to support the various operative parts in suitably elevated positions. The said frame or body is preferably provided with a flat top or table a whereon the work may be carried across and through the machine. As shown, the said table is provided with parallel guides a¹. Above the said table, the staplers B are supported and operated by a vertically reciprocating cross-bar C, supported in vertically arranged guide-way D. It will be readily seen that the said staplers can be of any suitable, known or approved construction, 85

and can be operated in any suitable or desired manner. Means can be employed for driving fastening devices, such as staples, nails or other devices of any suitable character. With the arrangement shown, a transverse rotary-shaft E is mounted in bearings e arranged below and each side of said table. This shaft is provided at each end with eccentric cams connected by eccentric straps and rods e with the reciprocating cross-head 95 C. Just below the table, a couple of transverse parallel shafts F are provided and connected at their ends through the medium of sprocket wheels and a sprocket chain f. It will be seen that these shafts F are also provided with pinions f¹ adapted to project upwardly and slightly above the upper surface of said table. For this purpose, the said table can be provided with recesses or apertures a², it being preferable that the 105 said pinions project upwardly through the

100

105

table at points just inside of the guides a^1 . It will be seen that the shaft E is also provided with a rotary crank-plate G provided with a slot g . The crank-pin g^1 is adjustable 5 along the length of this slot and is connected with a vibratory arm g^2 by means of links or pitmen g^3 . This arm g^2 is mounted upon an axis g^4 which is coincident with the axis of the ratchet wheel g^5 . The upper end of 10 said arm is provided with a pawl or dog g^6 adapted to engage the teeth of said ratchet wheel. With this arrangement, the gear-wheels f^2 , f^3 , f^4 , constitute the medium of power transmitting connections between the 15 said ratchet devices and the pinions f^1 . Consequently, when the shaft e is rotated, the staplers are operated, and the pinions f^1 are given an intermittent rotation by the said ratchet device.

20 As will hereinafter more fully appear, the vertically reciprocating anvil H is located directly below the middle stapler, and is operated by the cam h mounted on the shaft E.

25 Any suitable arrangement can be employed for feeding the wire from which the staples are formed, providing fastening devices of this particular character are employed. The wires, or other metal binding 30 strips, I can be mounted upon reels i, as shown, and guided through the staplers in any suitable manner. As shown in Figs. 6, 8, 9 and 10, the removable or portable work-holder J comprises a couple of trough-like 35 parallel side portions j connected by transverse bars j^1 . Flat springs j^2 are preferably located in the trough of each side portion and adapted to bear upon the inner sides of the cleats 1 comprised in the structure of 40 the blank shown in Fig. 7. It will be seen that the bottom of each trough-like side portion is also provided with blocks or spacing pieces j^3 adapted to properly separate the ends of said cleats. As illustrated, the 45 outer wall j^5 of each trough-like outer portion is higher than the inner wall j^6 . In addition, each side portion of the work-holder thus constructed is provided with racks j^7 having downwardly projecting 50 teeth. Thus constructed, the said work-holder is adapted to first receive the said cleats 1 of the box blank, and to have the transverse strips 2 then laid upon them, the ends of said strips engaging the inner surfaces of the side wall j^7 . In use, I may employ any number of work-holders of this character, it being understood that the same are successively loaded and then introduced into the machine. In this way, work- 55 men can be loading a great many of the said work-holders while an attendant takes them and passes them, one after the other, through the machine. When introduced into the machine, it will be seen that each 60 work-holder lies upon the table and that its

racks j^7 are engaged by the guides a^1 . The attendant pushes the work-holder into these guides until the said racks are engaged by the pinions f at that side of the machine, and the power for operating the machine 70 then causes the work-holder to move along with an intermittent feeding movement. By thus sliding in guide-ways, the side-portions of the work-holder serve as guide-blocks. The first staples driven by the 75 staplers serve to fasten the ends of the wires or other metal binding strips i to the wood or other material of which the blank is made. After this, the work-holder is then actuated so as to feed the work through the 80 machine, and so as to, in addition, pull the wires or other metal binding strips i through the staplers. It will be understood that each staple, when driven, straddles the wire or other metal binding strip and extends into the wood or other material of which the blank is composed. For the 85 staples which are driven at the side edges of the blank, the bottom walls of the troughs or side portions of the work-holders serve as 90 clenching blocks—that is to say, the points of the staples can be clenched on the bottoms of the said troughs or side portions. The staples which are driven in a line through the center of the blank are clenched 95 upon the anvil h which rises to receive the points of each staple. This anvil, of course, moves downwardly at the right time, for the purpose of permitting the bars j^1 of the work-holder to pass or move along. In this 100 way, each portable work-holder, when introduced into the machine, serves as the power transmitting connection through which the proper feeding movement is given to the wires I, and whereby these wires are 105 pulled along with the work and brought into position to be fastened in place by the staples or other fastening devices.

It is obvious that the broad idea of employing removable or portable work-holders 110 for giving both the work and the metallic binding a proper feeding movement through the machine, can be carried out or utilized in various ways. Practically, the only guiding to be done is with respect to the 115 cleats, as it essential that the latter be held to a straight course of travel beneath the staplers; and with respect to the binding wires, it being also essential that the wires be directed to and guided through or below 120 the staplers; the guides for the cleats consisting of the side-portions of the work-holder, and of the guide-ways in which the guide blocks on the work-holder are mounted. The guides for the binding wires may 125 be of any suitable character, but it is obvious that the side-portions of the work-holder constitute traveling or sliding guides for keeping the motion of the cleats direct. Furthermore, the work-holder is adapted to 130

receive or sustain the back-pull of the binding-wires.

The traveling guides for the cleats are provided; it will be seen, with means for preventing the drag or back-pull of the binding wires from causing endwise displacement of the cleats relatively to the said guides. Preferably, such means consist of miter-blocks inserted between the ends of the cleats, and adapted to keep the cleats properly separated while the work is advancing through the machine. In this way, it will be seen that the side portions of the work-holder are provided with means for preventing both lateral and endwise displacement of the cleats thereon, whereby such side portions constitute both guides for the cleats and power-transmitting connections for imparting motion through the cleats to the binding wires.

As will appear to those skilled in the art, the invention is not limited to the specific construction, organization and mode of operation hereinbefore described for illustration. On the contrary, the specific embodiment of the invention may be variously modified and the invention may be variously embodied within the scope of the subjoined claims.

30 I claim as my invention:

1. A machine for making box blanks comprising, in combination, work-controlling means for positioning a plurality of box sections in coöperative foldable relationship; mechanism for foldably connecting said sections—the work-controlling means and said mechanism being relatively movable to present different parts of the work to said mechanism; and means for positively 35 guiding the relative movement of the work-controlling means and said mechanism.

2. A machine for making box blanks comprising, in combination, work-controlling means for positioning a plurality of box sections in coöperative foldable relationship; mechanism for foldably connecting said sections; means for feeding the work relatively to said mechanism; and means for positively guiding the work in the direction 45 of its feeding movement.

3. A machine for making box blanks comprising, in combination, work-controlling means for positioning a plurality of box sections in coöperative foldable relationship; mechanism for foldably connecting said sections; means for positively feeding the work relatively to said mechanism; and means positively to guide the work during 55 a preliminary feeding movement prior to the commencement of the positive feed.

4. A machine for making box blanks comprising, in combination, work-controlling means for positioning a plurality of box sections in coöperative foldable relationship; mechanism for foldably connecting

said sections; means to support the work for a preliminary feeding movement toward said mechanism; means to engage the work and positively feed the same after said preliminary movement; and means positively 70 to guide the work in a straight line during said preliminary movement.

5. A machine for making box blanks comprising, in combination, cleat-positioning apparatus for a plurality of rows of cleats disposed substantially end to end in each row, constructed and arranged relatively to position adjacent cleat ends, in a row, in coöperative foldable relationship; mechanism for foldably connecting the adjacent 75 ends of cleats in the same row; and means for positively guiding and supporting each row of cleats for movement relatively to said mechanism.

6. A machine for making box blanks comprising, in combination, cleat-positioning apparatus for a plurality of cleats disposed substantially end to end, constructed and arranged relatively to position adjacent cleat ends in coöperative foldable relationship; mechanism for foldably connecting the adjacent ends of said cleats; means for feeding the cleats and said cleat-positioning means, relatively to said mechanism; and stationary guides for determining the path 85 of feeding movement of the cleats.

7. A machine for making box blanks comprising, in combination, cleat-positioning means for a plurality of cleats disposed substantially end to end, constructed and arranged relatively to position adjacent cleat ends in coöperative foldable relationship; preliminary work-supporting means to support the cleats with a frictional engagement permitting a preliminary feeding movement 100 of the cleats; fastener-applying mechanism for foldably connecting the adjacent ends of said cleats; feeding mechanism constructed and arranged positively to engage and feed the cleats, said feeding mechanism being located intermediate said preliminary work-supporting means and the fastener-applying mechanism; and means to guide the cleats during said preliminary feeding movement. 110

8. A machine for making box blanks comprising, in combination, cleat-positioning apparatus to receive cleats disposed substantially end to end, constructed and arranged relatively to position adjacent cleat ends in coöperative foldable relationship; fastener-applying means foldably to connect the adjacent cleat ends; and feeding mechanism for feeding the cleats relatively to the fastener-applying means, comprising an endless chain mounted to move in a path substantially parallel to the direction of feed of the cleats and power-transmitting means operatively connecting the chain and the cleats at different points along the line of feed; and means positively to guide the cleats. 125 130

9. A machine for making box blanks comprising, in combination, cleat-positioning apparatus to receive cleats disposed substantially end to end, constructed and arranged 5 relatively to position adjacent cleat ends in coöperative foldable relationship; fastener-applying means foldably to connect adjacent cleat ends; and feeding mechanism for feeding the cleats relatively to the fastener- 10 applying means, comprising a pair of shafts disposed transversely of the direction of feed of the cleats, sprocket wheels upon said shafts respectively, a sprocket chain mounted upon said wheels, means for driv- 15 ing the chain, and power-transmitting means operatively connecting the chain and cleats; and means for positively guiding the cleats in the line of feed.
10. A machine for making box blanks comprising, in combination, cleat-positioning apparatus for a plurality of rows of cleats disposed substantially end to end in each row, constructed and arranged relatively to position adjacent cleat ends in a 20 row, in coöperative foldable relationship; fastener-applying means for foldably connecting the adjacent ends of cleats in the same row; feeding mechanism for feeding the cleats relatively to the fastener-applying 25 means, comprising a pair of rotating wheels for each row of cleats, a shaft for each wheel of one row in common with the corresponding wheel of the other row, a sprocket chain connecting said shafts, and power-transmit- 30 ting means operatively connecting the cleats with said mechanism; and means for guiding the cleats in the line of feeding movement.
11. A machine for making metal-bound 35 box-blanks, comprising means for guiding the metallic binding onto the blank, suitable means for inserting fastening devices into the blank to secure the metallic binding thereto, and to secure cleats to the inner sur- 40 face of the blank, a power operated feeding device, and a portable work-holder adapted to carry the blank through the machine, said work-holder being adapted to be connected with said feeding device and, when so con- 45 nected, constituting a traveling guide for insuring a straight course of travel for the blank, and also constituting a medium through which a proper feeding movement is communicated through the cleats to the 50 said binding, in unison with the motion of the blank, said machine also comprising means for supporting the work-holder in position for movement in a straight line, and the parallel side portions of said work- 55 holder being provided with means for holding the said cleats end to end, in parallel and fixed relation thereto, and for preventing the binding from causing endwise dis- 60 placement of the cleats thereon, in combina- 65 tion with means for holding said work- holder in operative engagement with said feeding device.
12. A machine for making metal-bound box-blanks, comprising means for guiding or directing the metallic binding onto the blank, means for driving staples into the blank to secure the said binding thereto, and to secure cleats to the inner surface of the blank, a power operated feeding device, and a plurality of interchangeable work-holders 70 adapted to be loaded with the material from which the blanks are formed and then passed successively through the said machine, each work-holder being adapted to be connected with said feeding device and, when so connected, constituting a traveling guide for insuring a straight course of travel for the blank, and also constituting a medium through which the said feeding device communicates motion through the cleats to the 75 said binding, in unison with the motion of the blank, said machine also comprising means for supporting the work-holders in position for movement in a straight line, and the side portions of each work-holder being 80 provided with means for holding the said cleats end to end, in parallel and fixed relation thereto, and for preventing the binding from causing endwise displacement of the cleats thereon, in combination with means 85 for holding said work-holder in operative engagement with said feeding device.
13. A machine for making metal-bound box-blanks, comprising means for guiding the metal binding to the upper surface of the blank, means for inserting fastening devices for the purpose of securing the parallel binding strips to the blank, and to secure cleats to the inner surface of the blank, a power operated feeding device, and a portable work-holder adapted to support the said blank, said work-holder being adapted to be connected with said feeding device and, when so connected, constituting a traveling guide for insuring a straight course 90 of travel for the blank, and also constituting a medium through which motion is communicated through the cleats to the said binding strips by the said feeding device, said machine also comprising guideways for supporting and holding the work-holder in position for movement in a straight line, and the side portions of said work-holder being 95 provided with means for holding the said cleats end to end, in parallel and fixed relation thereto, and for preventing endwise displacement of the cleats thereon.
14. A machine for making metal-bound box-blanks, comprising means for directing the metal binding to the surface of the blank, means for inserting fastening devices to secure the metallic binding to the blank, and to secure cleats to the inner surface of the blank, and a portable work-holder adapted to carry the blank and serve as a traveling 100
- 105
- 110
- 115
- 120
- 125
- 130

- guide for insuring a straight course of travel for the blank, power transmitting connections whereby the work-holder serves as the medium through which a feeding movement 5 is communicated through the cleats to said binding, together with stationary guides which engage the said work-holder and thereby determine the direction of feed of the said cleats and binding, as well as of the said traveling guide, the side portions of said work-holder being provided with means for holding the said cleats in parallel and fixed relation thereto, and for preventing endwise displacement of the cleats thereon.
- 15 15. A machine for making metal-bound box-blanks, comprising means for directing the metal binding to the surface of the blank, means for inserting fastening devices to secure the metallic binding to the blank, and to secure cleats to the inner surface of the blank, a power-operated intermittent feeding device, a portable work-holder adapted to be loaded with the material from which the blank is made and then inserted in the machine, said work-holder being adapted to be connected with the said feeding device and, when so connected, to serve as a traveling guide for insuring a straight course of travel for the blank, and also as the medium through which an intermittent feeding movement is communicated through the cleats to the said metallic binding, from the said feeding device, together with stationary guides which engage the said work-holder and thereby determine the direction of the feeding movement of the said cleats and binding, as well as of the said traveling guide, the side portions of said work-holder being provided with means for holding the said cleats in parallel and fixed relation thereto, and for preventing the drag or back-pull of the binding from causing endwise displacement of the cleats thereon.
16. A machine for making metal-bound box-blanks, comprising means for directing the metal binding to the surface of the blank, means for inserting fastening devices to secure the metallic binding to the outer surface of the blank, and to secure cleats to the inner surface of the blank, a traveling work-holder having parallel side portions adapted to hold the cleats end to end, and provided with means for engaging the ends of the cleats, each side portion having springs for holding the cleats in place, and power transmitting connection for operating said work-holder, the side portions of the work-holder constituting sliding guides for keeping the endwise motion of the cleats direct, and also constituting connections by which power or motion is communicated by the machine through the cleats to the said binding, in combination with means for maintaining said work-holder in operative connection in the said feeding device.
17. A machine for making metal-bound box-blanks, comprising means for directing the metal binding to the surface of the blank, means for inserting fastening devices to secure the metallic binding to the outer surface thereof, power-operated means including a traveling work-holder for communicating intermittent motion through the cleats to said binding, said work-holder being provided with side portions adapted to receive and hold the said cleats in fixed relation thereto, and means for holding the said work-holder to a straight line of travel while the cleats are subject to the drag or back-pull of the metal binding, and whereby the said side portions of the work-holder slide as guides to keep the endwise motion of the cleats direct. 70
18. A machine for making metal-bound box-blanks, comprising means for directing the metal binding to the surface of the blank, means for effecting an attachment of the metallic binding to the outer surface of the blank, and of cleats to the inner surface of the blank, together with power operated means including a plurality of separate longitudinally movable members for communicating motion through the cleats to said binding, said members being adapted to engage and move the cleats endwise, and guide the same, and means for holding said members to straight lines of travel. 85
19. A machine for making metal-bound box-blanks, comprising means for directing the metal binding to the surface of the blank, means for inserting fastening devices to secure the metallic binding to the outer surface of the blank, and to secure cleats to the inner surface of the blank, a traveling work-holder adapted to engage and move the cleats endwise, guide the same, and prevent endwise displacement of the cleats thereon, together with means for operating said work-holder and thereby communicating motion through the cleats to said binding, and means for holding said work-holder to a straight line of travel. 100
20. A machine for making wire-bound box-blanks, comprising reels on which the binding-wires are carried, means for inserting fastening devices to secure the wires to the outer surface of the blank, and to secure cleats to the inner surface thereof, and means including a portable work-holder for pulling the wires off from the reels, and for communicating a step-by-step motion to the said cleats and wires and other portions of the blank, said work-holder being adapted to be loaded with the materials and then inserted in the machine, said machine also comprising means for supporting the work-holder in position for movement in a straight line, and the side portions of said work-holder being provided with means for holding the said cleats in parallel and fixed 115
- 120
- 125
- 130

relation thereto while subject to the drag or back-pull of the binding wires, including devices which hold the work-holder against lateral and upward displacement.

5 21. Means for making box-blanks, including a portable carriage constituting an adjunct applicable to a blank-stitching machine, together with guides for directing binding wires onto the blank, said carriage being provided with parallel cleat-supporting and guiding members for spacing the cleats with relation to each other, and with means for holding the cleats against endwise displacement while subject to the drag or back-pull of the wires, in combination with means for holding said carriage against displacement from its path of travel.

22. Means for making box-blanks, comprising in combination a machine provided with staple drivers, operating means therefor, a frame-like carriage constituting an adjunct applicable to the machine and insertible into and removable therefrom, the carriage constituting means for positioning and holding assembled blank material in proper relation for a box-blank, and for guiding the same, feed mechanism in the machine for engaging and moving the inserted carriage below the staple drivers, and means for guiding binding wires onto the blank, said carriage being provided with means for holding the cleats against endwise

displacement while subject to the drag or back-pull of the wires, in combination with means for holding said carriage against displacement from its path of travel. 35

23. In a machine of the class described, a fastener driving mechanism, a portable work holder having provision for positioning opposed cleats and side material extending between the same, means to positively advance the work holder step by step for presentation of the work to said mechanism, and means positively to guide the work holder in its advance. 40

24. In a machine of the class described, a gang stapler, comprising a plurality of stapling mechanism operating in a plane, parallel guides extending transversely across said plane, means to advance assembled cleats and side material intermittently across said plane under control of said guides, said means including a portable work holder having provisions for positioning the cleats and side material, and means to supply binding wires for attachment by said staplers to the side material and cleats. 50

Signed by me at St. Joseph, Berrien county, Michigan, this nineteenth day of October, 1904.
